UNITED STATES PATENT OFFICE.

JOHN S. WAKIMOTO, OF GRAND ISLAND, NEBRASKA.

CHALK-LINE HOLDER AND REEL.

1,251,712.

Specification of Letters Patent.

Patented Jan. 1, 1918.

Application filed June 1, 1917. Serial No. 172,311.

To all whom it may concern:

Be it known that I, JOHN S. WAKIMOTO, a subject of the Emperor of Japan, residing at Grand Island, in the county of Hall and 5 State of Nebraska, have invented certain new and useful Improvements in Chalk-Line Holders and Reels, of which the following is a specification.

This invention relates to improvements in 10 combined chalk holders and chalk line reels, and has for one of its objects to improve the construction and increase the efficiency and utility of devices of this character.

Another object of the invention is to provide 15 a device of this character including means for supporting chalk in powdered form in position to be applied to a chalk line when drawn through the same and with means for winding the chalk line upon a reel 20 before and after use and disposing of the surplus chalk which would otherwise be carried with the line upon the reel.

Another object of the invention is to provide 25 a simply constructed device whereby the supply of chalk may be readily renewed as required.

With these and other objects in view, the invention consists in certain novel features of construction, as hereinafter shown and 30 described and then specifically pointed out in the claim; and in the drawings illustrative of the preferred embodiment of the invention—

Figure 1 is a plan view of the improved 35 device;

Fig. 2 is a longitudinal section on the line 2—2 of Fig. 1;

Fig. 3 is a transverse section on the line 3—3 of Fig. 1.

Corresponding and like parts are referred 40 to in the following description and indicated in all the views of the drawings by the same reference characters.

The improved device comprises a supporting body represented as a whole at 10, and which may be formed to represent a lady's shoe as shown. The body 10 is formed with an upwardly opening forward recess 11 and an upwardly opening rearward recess 12.

The recesses 11—12 are united at their lower 45 portions by a longitudinally directed passage 13, while another passage 14 leads from the lower portion of the forward recess 11 through the forward end of the body. For 50 the purpose of this description the "toe" portion 15 of the body will be referred to as

the forward terminal, while the "heel" portion of the body will be referred to as the rearward terminal, hence the recess 11 is referred to as the forward recess, while the recess 12 is referred to as the rearward recess. The hollow portion beneath the instep of the body 10 constitutes a transverse cavity indicated at 16, and a discharge passage 17 connects the rearward recess 12 with the cavity 16. The opening which provides access to the recess 17 is less in area than the cavity 11 so that the portion of the body 10 which surrounds the opening into the cavity 11 overhangs the latter as represented 55 at 18. Mounted for rotation upon the body 10 above the recess 12 is a shaft 19 carrying a reel device 20. The chalk line indicated as a whole at 21, is connected at its inner end to the reel device and leads thence through the connecting passage 13, the recess 11 and outlet passage 14 as shown in Fig. 1, and united at its outer end to a supporting peg 22, the latter having a spur 23 adapted to be driven into the body upon which the chalk line is to 60 be produced. By this means when the crank 24 of the reel is rotated in one direction the line 21 will be wound upon the reel until the peg 22 engages the forward end 15 of the body, and when the line is to be used it is 65 withdrawn to the required extent by power applied to the peg. The chalk is initially in powdered form and compressed into the recess 11 through the contracted opening, which action will cause the chalk to engage 70 beneath the overhanging portions 18 and engage the line 21 as it is passed through the recess. The powdered chalk being compressed within the recess is caused to assume a semi-solid condition, and is prevented 75 from displacement by the overhanging portions of the recess, and will not therefore be displaced when in use, while at the same time will effectually apply a sufficient quantity of the chalk to the line to produce the 80 requisite chalk mark when the line is stretched over an object or structure and "snapped".

The entrance to the cavity 18 is preferably provided with a closure of yieldable 85 material such as compressed cotton, felt, wool or the like and indicated at 24. As the chalk wears away pressure applied to the closure member 24 will cause the chalk to follow up the line, and when the mass of 90 chalk within the recess is consumed a fresh supply can be inserted from above, or the 95

- chalk may be supplied in small quantities as fast as worn away from below. The plug member 24 being compressible may be caused to follow up the chalk as the latter is used, thus retaining the chalk in constant contact with the line. The "heel" portion 25 of the body 10 serves as a grip which will be engaged by the fingers of one hand while the reel is being actuated by the other.
- 10 The improved device is simple in construction, can be constructed of any suitable material of any suitable size and operates effectually for the purposes described.
- 15 Having thus described the invention, what is claimed as new is:
- 10 A device of the class described comprising an oblong body having upwardly opening rearward and forward recesses and a downwardly and transversely opening recess, said 20 forward recess having a line passage leading

therefrom, said forward and rearward recesses being connected by a line passage, and said downwardly and transversely opening recess and said rearward recess having a communicating opening, a line reel mounted in said rearward recess, a line leading from said reel and through said passages and through the forward recess, and means for maintaining powdered chalk within the forward recess and in contact with the line 30 therein, said communicating opening providing means for the escape of surplus chalk which may be carried by the line when being wound upon the reel and said downwardly opening transverse recess coacting 35 with the portion of the body rearwardly thereof to form a hand grip for supporting the body.

In testimony whereof I affix my signature.

JOHN S. WAKIMOTO. [L. S.]
